A. V. JENSEN,

TIE PLATE.

APPLICATION FILED NOV. 13, 1915.

1,190,906.

Patented July 11, 1916.

Inventor

A. V. JENSEN

By Watson E. Coleman

Attorney

UNITED STATES PATENT OFFICE.

ALEXANDER V. JENSEN, OF DEVILS SLIDE, UTAH.

TIE-PLATE.

1,190,906.

Specification of Letters Patent. Patented July 11, 1916.

Application filed November 13, 1915. Serial No. 61,371.

To all whom it may concern:

Be it known that I, ALEXANDER V. JENSEN, a citizen of the United States, residing at Devils Slide, in the county of Morgan and State of Utah, have invented certain new and useful Improvements in Tie-Plates, of which the following is a specification, reference being had to the accompanying drawings.

10 This invention relates to certain improvements in tie plates; and it is an object of the invention to provide a novel and improved device of this general character which serves effectually to prevent the spreading of rails.

15 It is also an object of the invention to provide a novel and improved device of this general character whereby a member may be employed for supporting the head or tread portion of a rail at a curve.

20 The invention consists in the details of construction and in the combination and arrangement of the several parts of my improved tie plate whereby certain important 25 advantages are attained and the device is rendered simpler, less expensive and otherwise more convenient and advantageous for use, all as will be hereinafter more fully set forth.

30 The novel features of the invention will be carefully defined in the appended claims.

In order that my invention may be the better understood, I will now proceed to describe the same with reference to the accompanying drawings, wherein—

35 Figure 1 is a view in top plan illustrating a tie plate constructed in accordance with an embodiment of my invention, one of the rails of the track-way being omitted; Fig. 2 is a view in side elevation of the device as disclosed in Fig. 1; Fig. 3 is a sectional view taken substantially on the line 3—3 of Fig. 1; and Fig. 4 is a view in perspective of the supporting member detached, adapted 40 to be employed at a curve in the track-way.

45 As disclosed in the accompanying drawings, 1—1 denote substantially rectangular plates adapted to rest upon the upper surface of a tie T and integrally connected by the interposed web 2 of a width materially less than the width of the plates 1, said web and adjacent end portions of the plates being reinforced by the longitudinally disposed rib 3 pressed therefrom and extending 50 upwardly relative to the tie T. The rib is

substantially in the form of an inverted V in cross section and gradually increased in height from its ends toward the center.

Each of the plates 1 has pressed upwardly 60 therefrom the transversely disposed ribs 4 substantially in the form of an inverted U and on the flat upper faces of which the base of a rail R is adapted to rest and said plate is further provided with the upstanding 65 shoulder 5 adapted to contact with the free longitudinal edge of the outer flange 6 of the rail. The inner transverse rib 4 of each plate 1 is also provided with the openings 7 through which the clamping members 8 are 70 adapted to be directed, said openings 7 being in staggered relation. Each of the plates 1 is also provided with similar openings intersecting the upstanding shoulder 5 thereof. It is also to be observed that the 75 outer end portion of each of the plates 1 is flat and is provided with the openings 9 adapted to register with the openings 10 formed in the plate 11 through which anchoring members 12 are adapted to be directed. Integrally formed with the plate 11 is an upstanding and inwardly inclined 80 brace member or post 14 adapted to engage the under portion of the head or tread of the rail R whereby said rail is effectively reinforced, especially at a curve in the track-way.

85 From the foregoing description, it is thought to be obvious that a tie plate constructed in accordance with my invention is 90 of an extremely simple and comparatively inexpensive nature and is particularly well adapted for use by reason of the convenience and facility with which it may be assembled, and it will also be obvious that my invention is susceptible of some change and modification without material departure 95 from the principles and spirit thereof and for this reason I do not wish to be understood as limiting myself to the precise arrangement and formation of the several parts herein shown in carrying out my invention in practice.

100 I claim:

1. In combination, two longitudinally 105 aligned plates provided with transversely disposed upstanding ribs upon which rails are adapted to rest, each of said plates being provided with an upstanding shoulder adapted to contact with the free longitudinal edge of the outer flange of the coating rail, and a web interposed between and in-

tegrally connected with the opposite ends of the plates, said web and the adjacent end portions of the plates being provided with an upstanding rib extending longitudinally of the web, each of said plates having its inner transverse rib provided with bolt openings.

2. In combination, two longitudinally alined plates with transversely disposed up-
10 standing ribs upon which rails are adapted to rest, each of said plates being provided with an upstanding shoulder adapted to contact with the free longitudinal edge of the outer flange of the coating rail, and a
15 web interposed between and integrally con-

nected with the opposite ends of the plates, said web and the adjacent end portions of the plates being provided with an upstanding rib extending longitudinally of the web, each of said plates having its inner trans- 20 verse rib provided with bolt openings, each of the plates having also disposed there-through additional openings intersecting the upstanding shoulder.

In testimony whereof I hereunto affix my 25
signature in the presence of two witnesses.

ALEXANDER V. JENSEN.

Witnesses:

I. BALL,
FRANK H. NORBERG.
